UNITED STATES PATENT OFFICE.

WALTER J. MERRIMAN, OF LAKE VIEW, OHIO.

WIRE REEL.

Application filed December 19, 1924. Serial No. 756,930.

To all whom it may concern:

Be it known that I, WALTER J. MERRIMAN, a citizen of the United States, residing at Lake View, in the county of Logan and State of Ohio, have invented certain new and useful Improvements in a Wire Reel, of which the following is a specification.

This invention relates to an improved wire reel of the type used for winding wire thereon or paying out wire therefrom.

It is my object to generally improve upon reels of this class by providing one of comparative simplicity and durability which is practical and such in construction as to render its use highly desirable for the purpose specified.

The primary feature of the invention is a collapsible rim constructed in such a manner as to permit the bundle of rolled wire to be bodily removed or placed in position thereon.

More specifically, it is a feature to provide a rigid spider embodying radiating arms upon which channel shaped sectors are movably mounted in forming a collapsible rim.

Another important feature of the invention is the novel expanding and contracting means for the rim.

Other objects, features and advantages of the invention will become apparent from the following description and drawing.

In the accompanying drawing forming a part of this application and in which like numerals are employed to designate like parts throughout the same:

Figure 1 is a top plan view of a wire reel constructed in accordance with the present invention showing the same expanded for use.

Figure 2 is a view like Figure 1 showing the rim collapsed to permit removal or application of the wire.

Figure 3 is an enlarged detail section of the spider hub.

Figure 4 is an enlarged detail perspective view of one of the outer ends of a spider arm.

Figure 5 is a detail perspective view of one of the segments or sectors of the collapsible rim structure.

Referring to the drawings in detail it will be observed that the reference character 1 designates what may be generally referred to as a spider, the same comprising a plurality of circumferentially spaced arms 2

radiating from a central hub 3. Although the spider could be constructed otherwise, it is preferably in the form of a single casting and the arms are in the form of I-beam. The hub at the center rises to a predetermined elevation above the arm as shown better in Figure 3. As plainly shown in Figure 4, the outer end of each arm is formed with outwardly diverging extensions 4 connected together at their point of juncture by a web 5. The web in turn is provided with an outstanding boss 6 which serves in a manner to be later described. It may be conveniently stated here that the outer end of the extensions 4 are apertured as at 7 to serve as a novel mounting means for the collapsible rim to be described.

As before intimated the rim employed in conjunction with the present device is capable of being varied in diameter to facilitate application and removal of the wire after it is in a rolled state. In the present instance I prefer to use a plurality of circumferentially spaced arcuate segments 8, each being substantially channelled shaped in cross section. At its ends it is provided with inwardly extending ears 9 and these are pivotally connected to the apertured ends of the aforesaid extensions 4. Connected to the approximate center of each segment is an apertured lug 10. With this arrangement it is obvious that the sectors or segments 8 may be swung from the horizontal plane shown in the drawing to the inclined positions shown in Figure 2 for collapsing the rim for the purpose specified.

For the purpose of expanding and contracting the rim or collapsing it, I provide novel means. In the present instance I prefer to provide a center plate 11 provided on its under side with a plurality of circumferentially spaced V-shaped ribs 12 receivable in correspondingly shaped grooves formed in the upper ends of the aforesaid hub 3. The plate 11 is reinforced at its center as indicated at 13 and is provided with a central bore aligning with a bore formed in the hub 3, there being a bolt 14 passing through these bores and having its threaded end projecting beyond the reinforcement 13. A thumb nut 15 is threaded onto the bolt. The reinforcement 13 is provided with diametrically opposite handles 16 by means of which the plate 11 is turned. At its corners, this plate is formed with openings and the inner ends of radiating

- opposed links or rods 17 are connected with the plate. The outer ends of the rods are shaped as shown in Figure 1 and pivotally connected with blocks or their equivalent 18 which are in turn pivotally connected to the aforesaid lugs 10. The blocks 18 are preferably bifurcated and the furcations straddle the lugs and are pivotally connected thereto.
- 10 Directing attention again to Figure 4 it will be seen that a hooked bolt 19 extends through the boss 6 and a thumb nut 20 is screwed onto the threaded end thereof. Here I would state that the device shown and described is particularly adapted for connection to the spokes of a vehicle wheel so that the latter may be used as a means for rotating the wheel for winding wire or unwinding as the case may be. The bolt 19 may be used for the purpose of connecting the device to the vehicle wheel in an obvious manner.

Assuming that the wire has been wound upon the rim of the improved wheel and it is desired to bodily remove the roll, the handles 16 are simply gripped and moved in a direction from right to left, carrying the plate 11 around with them. Of course, before the plate 11 can be turned, the thumb nut 15 must be loosened to disengage the ribs 12 from the grooves in which they are seated. By thus turning the plate 11, a radial and circumferential pull is exerted upon the links 17. Inasmuch as these are connected at their outer ends to the lugs 10 on the sectors 8, it is clear that the latter will be swung upon their pivots from the plane shown in Figure 1 to the inclined positions shown in Figure 2. The ends of the sectors will then be substantially in abutting relation and the diameter of the rim is decreased to such an extent as to facilitate application and removal of wire. If it is desired to maintain the rim in collapsed state, the thumb nut 15 can be tightened and when the parts are in the position shown in Figure 2, the ribs 12 will have moved through one quarter of a revolution, thus permitting them to be seated in the right angularly disposed grooves in the top of the hub 3. The grooves in the top of the latter may be said to be in pairs, the pairs extending at right angles to each other so that the plate 11 may be positively held in the positions shown in Figures 1 and 2 respectively.

From the foregoing description and drawing, it will be apparent that I have evolved and produced a very novel wire reel structure capable of facilitating application and removal of rolled wire, the same comprising a rigid spider carrying a collapsible rim composed of pivotally mounted channel shaped sectors for effectively confining the strands of wire and these sectors being si-

multaneously swung upon their pivots to inclined position for ready application or removal of the wire.

Although I have shown and described the preferred embodiment of the invention, it is to be understood that minor changes coming within the field of invention claimed may be resorted to if desired.

Having thus described the invention, what I claim is:

1. A wire reel of the class described comprising a spider embodying a plurality of radiating arms, and a collapsible rim structure supported on the outer ends of the arms, said rim being composed of a plurality of flanged sectors, and means for operating said sectors for collapsing the rim, said sectors being pivotally mounted on the outer ends of the arms to swing in a direction at right angles to the axis of rotation of said spider.

2. A wire reel of the class described comprising a spider embodying circumferentially spaced radiating arms provided at their outer ends with diverging extensions, an arcuate sector pivotally supported between pairs of the arms and connected to said extensions, each sector being of channel shaped cross section, links pivotally connected at their outer ends to the intermediate portion of the sectors, and means mounted upon the center of the spider for exerting an inward and circumferential pull upon said links for moving said sectors upon said pivots.

3. A wire reel comprising a spider including a central hub and a plurality of circumferentially spaced arms radiating therefrom, said hub being provided in its outer end with intersecting grooves, arcuate sectors pivotally mounted between pairs of the aforesaid arms, said sectors cooperating to form a collapsible rim structure and being mounted to swing in a direction at right angles to the axis of rotation of the spider, a plate mounted for rotation upon said hub, said plate being provided with a rib adapted to be selectively seated in the aforesaid grooves, a turning handle carried by said plate, and links pivotally connected at their outer ends to the intermediate portion of the sector and connected at their inner ends to the plate, whereby when the latter is rotated an inward and circumferential pull will be exerted upon said links for swinging said sectors upon their pivots.

4. A wire reel of the class described comprising a rotary spider including a central hub provided at its free ends with intersecting grooves, and circumferentially spaced arms radiating from said hub, said arms being provided at their outer ends with diverging extensions connected together by intervening webs, hook-bolts car-

ried by said webs, a rotary plate cooperating with said hub, said plate being provided at its inner face with a rib adapted to be selectively seated in said groove, said plate being also provided with a turning handle, channel-shaped arcuate sectors arranged between the extensions at the outer ends of said arms, means pivotally connecting the sectors with the extensions to permit the sectors to swing in a direction at right angles to the axis of rotation of the spider, and links connected at their outer ends to the intermediate portions of said sectors and at their inner ends to said plate.

15 5. A wire reel of the class described comprising a mounting having a sectional rim on its periphery, said sections being mounted in a manner to permit them to be disposed normally in a plane with the mounting, but permitting them to be swung in a direction at right angles to the axis of rotation of the mounting.

20 6. In a device of the class described, a support, a rim having a segmental por-

tion pivoted at its ends to said support, and rotatable means having connection with said portion intermediate the ends thereof for swinging the same, whereby rotation of said means in one direction operates to swing said portion transversely to and inwardly at right angles from the periphery of the rim for decreasing the distance between the axis of said support and the periphery of said segmental portion and thereby collapsing the rim.

25 7. In a device of the class described, a support, a rim having a plurality of segmental sections movably connected at opposite ends thereof to said support, a rotatable member on said support, and means 40 for connecting said member in an intermediate portion of individual sections whereby rotation of said member conjointly swings said sections at right angles to and inwardly from the periphery of the rim.

30 35 45 In testimony whereof I affix my signature.

WALTER J. MERRIMAN.
